CLAIM

The ornamental design for a mobile phone supporter for mount on automobile air outlet, as shown and described.

DESCRIPTION

FIG. 1 is a perspective view of a mobile phone supporter for mount on automobile air outlet, showing my new design.

FIG. 2 is a front view thereof.

FIG. 3 is a left view thereof.

FIG. 4 is a right view thereof.

FIG. 5 is a top view thereof; and,

FIG. 6 is a bottom view thereof.
